UNITED STATES PATENT OFFICE.

WILLIAM A. BOND, OF LYNN, MASSACHUSETTS, ASSIGNOR TO UNITED SHOE MACHINERY COMPANY, OF PATERSON, NEW JERSEY, A CORPORATION OF NEW JERSEY.

BUFFING-MACHINE.

1,168,473.

Specification of Letters Patent. Patented Jan. 18, 1916.

Application filed August 9, 1911. Serial No. 643,180.

To all whom it may concern:

Be it known that I, WILLIAM A. BOND, a citizen of the United States, residing at Lynn, in the county of Essex and State of Massachusetts, have invented certain Improvements in Buffing-Machines, of which the following description, in connection with the accompanying drawings, is a specification, like reference characters on the drawings indicating like parts in the several figures.

This invention relates to grinding, polishing or similar machines and is herein illustrated in connection with a machine for buffing the soles of boots and shoes.

In buffing or scouring boots and shoes it is desirable to imitate as closely as possible the hand-scouring operation in which the hand of the operator describes a series of closed curves which overlap one upon the other. In practice, however, it has been found that a rotating roll has many points of advantage, and the problem, therefore, has been to give to the operative surface of such a roll the desired movement. With this end in view buffing rolls have been simultaneously reciprocated and rotated; but, although the compound movement thus produced is very effective, the general object of the present invention is to produce a movement which approximates more closely the movement of the hand operator.

To this end, one feature of the present invention consists in the combination with a rotating operating member of means for moving said member in an orbital path. And by "orbital path" is meant any path which returns into but not upon itself; that is, a closed path described by a body which moves at all times in a forward direction with regard to its path as distinguished from a closed path which returns upon itself as in the case of reciprocation. In the illustrative machine the operating member takes the form of a roll which is rotated about its longitudinal axis; and this combined axial rotation and bodily movement in an orbital path results in a compound movement which approximates very closely the movement of the hand of a hand operator and produces upon the sole of the shoe a surface which takes an exceedingly satisfactory finish during the subsequent polishing operation.

Considered from a different aspect another feature of the invention consists in the combination with an operating member and means for rotating said member of means for moving said member in a predetermined path at an angle to its axis of rotation, this transverse movement being in the illustrative machine part of an orbital movement referred to above.

The shoe is ordinarily presented to the roll at an angle with the toe pointing downwardly, the angle varying somewhat with the individual operator, and in the present machine the angle at which the shoe is presented is determined by the plane of the orbital path of the roll.

Accordingly, another feature of the present invention comprises means for varying the inclination of the orbital path of the roll so that the machine may be readily adjusted to conform to the preference of the given operator.

These and other features of the invention including certain details of construction and combinations of parts will be described in connection with an illustrative machine and pointed out in the appended claims.

Referring to the accompanying drawings, Figure 1 is a front elevation of the machine in which the present invention is embodied; Fig. 2 is a side elevation of a portion of the machine, certain parts being shown in section to illustrate more clearly the mechanism by which the journal boxes are actuated. In this figure one of the possible angular positions of the bracket is indicated in dotted lines; and Fig. 3 is a detail principally in section showing a modification of the means for compelling the roll shaft to move with the journal boxes.

The frame 1 of the machine is provided with two guideways 3 designed to receive guides 5, said guides being held in position by screw bolts 7 which pass through slots not shown in the bottom of the guideways and are threaded into said guides. These guides 5 are formed on and support brackets 9 which in turn support casings 11, the lower parts of said casings in the illustrated machine, being integral with said brackets, while the upper parts consist of plates held in place by means of screw bolts 12. The interiors of these casings are rectangular in

cross section, and the upper and lower walls serve as slide bearings for the journal boxes 13, said boxes being thus movable in any horizontal direction.

5 The roll shaft 15 carrying the operating members 17, herein shown as buffing rolls, is rotatably mounted in the journal boxes 13 and has fast to one end a pulley 19, to which power may be applied from any convenient source, and fast to the opposite end a pulley 21 from which power may be transmitted by means of a belt to the pulley 23 on the counter shaft 25. This counter shaft is mounted in bearings in the brackets 9 and 10 is adapted to be swung outwardly with the brackets in the manner indicated in Fig. 2. In order to maintain the belt which passes over the pulleys 21 and 23 at a constant tension the guideways 3 are arcs of circles 15 struck from the center of the roll shaft 15.

20 The counter shaft has fast to it spiral gears 27 which mesh with similar gears 29 fast to upright shafts 31. Each shaft 31 is mounted in bearings 33 and 35 formed in the brackets 9 and has its upper end journaled in a bearing 37 formed in the upper wall of the casing 11. Each journal box 13 is formed with an eccentric strap 39 which encircles an eccentric 41 formed on the upper part of each upright shaft 31, each eccentric being encircled by a bushing 43. With this construction a movement transverse to the axis of rotation of the shaft 15 may be imparted to the journal boxes 13, said movement in the illustrated machine being part 25 of the orbital movement of said boxes. In order that the roll shaft 15 may partake properly of the movement of the boxes so as to be moved longitudinally of its axis as 30 well as transversely thereto, said shaft carries near one end a fixed collar 45 which bears against the outer end of the right hand journal box, as viewed in Fig. 1, there being at the opposite end of the shaft a loosely 35 mounted washer 47 held against the outer end of the left hand box by means of a spring 49 which bears with one end against said washer and with the other against the pulley 19.

40 The eccentricities in the illustrative machine are set at the same angle and consequently the two ends of the roll shaft are in similar points of their orbits at any given moment, so that a given point on either roll describes 45 a circle. The spiral gears 29, however, are adjustably held in place by washers 51 and nuts 53 so that by loosening one of said nuts the corresponding shaft 31, and with it the corresponding eccentric, may be set at any 50 desired angle. For example, let it be supposed that the eccentricities 41 are set 180° apart. The paths of any two similarly located points on the two rolls will then no longer be circles, nor will said points be in 55 corresponding portions of their respective

paths at any given moment. The paths in this case will approximate two isosceles triangles having their apexes in proximity. It will be unnecessary to consider further specific examples of the relative angular positions at which the eccentrics may be set, but it should be noted that, if desired, one of the gears 29 may be removed whereby a movement will be imparted to the rolls which will be quite different from either of the movements referred to above. It is thus possible to select from a great variety of possible movements of the rolls the particular movement desired. As thus far described, the plane of the orbital paths of the boxes and hence of the rolls is horizontal. The purpose of the guideways 3 and guides 5, however, is to permit the said paths to be inclined to the horizontal; and, in order to facilitate the adjustment of the bracket 9 as well as to hold it more firmly in adjusted position, slotted fingers 55 are pivoted to the brackets 9 at 57 and may be clamped to the frame in any desired position by means of the bolts 59. In case that the eccentrics are set at the same angle so that the journal boxes describe similar orbits, the spring 49 is not essential, and in Fig. 3 said spring has been omitted and in its place has been substituted a collar 61 fast to said shaft. It should be noted that various other arrangements of collars and springs may be used, if desired, to compel proper movement of the shaft with the boxes.

55 The operation of the machine is as follows: The eccentrics are set in the desired angular relation with respect to each other in the manner described; the brackets 9 are adjusted to the desired angular position, and power is applied to the machine. The operator then presents the bottom of the sole of a boot or shoe to the under side of the rolls. The rolls, moving in the path described above, will thoroughly scour the bottom of the shoe, the only manipulation required of the operator being to present the sole of the shoe progressively to said rolls.

60 Although the invention has been set forth in connection with a particular machine, it should be understood that the invention is not limited in the scope of its application to the particular machine shown and described.

Having fully described my invention, what I claim as new and desire to secure by Letters Patent of the United States is:—

65 1. A machine of the class described having, in combination, an operating member, a support for said member, power actuated means for moving said member and its support in an orbital path, and means for varying the plane of said path.

70 2. A machine of the class described having, in combination, a rotary shaft, a plurality of buffing rolls mounted thereon, and means for moving said shaft in an orbital

path the plane of which contains the axis of said shaft.

3. A machine of the class described having, in combination, an operating roll, means for rotating said roll, means for moving said roll longitudinally of its axis as well as transversely thereto, and means for varying the inclination of the plane of said transverse movement to the horizontal.

10 4. A machine of the class described having, in combination, an operating roll, means for rotating said roll, means for moving said roll in an orbital path, and means for varying the plane of said path.

15 5. A machine of the class described having, in combination, a shaft, an operating member mounted thereon, means for rotating said shaft, and means for moving said shaft in an orbital path the plane of which contains the axis of said shaft.

20 6. A machine of the class described having, in combination, a shaft, an operating member mounted thereon, means for rotating said shaft, means for moving said shaft in an orbital path, and means for varying the plane of said path.

25 7. A machine of the class described having, in combination, a buffering roll, a shaft upon which said roll is mounted, journal boxes in which said shaft is rotatable, casings supporting said boxes, means for rotating said shaft, and means for moving said boxes in said casings.

30 8. A machine of the class described having, in combination, a buffering roll, a shaft upon which said roll is mounted, journal boxes in which said shaft is rotatable, casings supporting said boxes, means for rotating said shaft, means for moving said boxes in said casings, and means for adjusting said casings angularly.

35 9. A machine of the class described having, in combination, a buffering roll, a shaft upon which said roll is mounted, journal boxes in which said shaft is rotatable, casings in which said boxes are slidably, means for rotating said shaft, and means for moving said boxes in orbital paths in said casings.

40 50 10. A machine of the class described having, in combination, a buffering roll, a shaft upon which said roll is mounted, journal boxes in which said shaft is rotatable, casings in which said boxes are slidably, means for moving said boxes in orbital paths in said casings, and means for varying the angular position of said casings.

45 60 11. A machine of the class described having, in combination, a buffering roll, a shaft upon which said roll is mounted, journal boxes in which said shaft is rotatable, casings in which said boxes are slidably, means for rotating said shaft, brackets by which said casings are carried, said brackets being provided with guides, guideways in which

said guides are slidable, and means for clamping said brackets in adjusted position.

12. A machine of the class described having, in combination, a buffering roll, a shaft upon which said roll is mounted, a journal 70 box in which said shaft is rotatable, a casing in which said box is slidable, said box being provided with an eccentric strap, a second shaft arranged at an angle to said roll shaft, said second shaft being formed 75 with an eccentric arranged to coöperate with said eccentric strap, and means for rotating said two shafts.

13. A machine of the class described having, in combination, a buffering roll, a shaft 80 upon which said roll is mounted, a journal box in which said shaft is rotatable, a casing in which said box is slidable, said box being provided with an eccentric strap, a bracket by which said casing is carried, a 85 second shaft rotatably mounted in said bracket and formed with an eccentric arranged to coöperate with said eccentric strap, means for rotating said two shafts, and means for adjusting said bracket an- 90 gularly.

14. A machine of the class described having, in combination, an operating member, a rotary shaft upon which said member is mounted, mechanism for causing both ends 95 of said shaft to move toward the operator simultaneously and similarly to recede from him, and means whereby said mechanism may be adjusted to cause one end to move toward said operator while the other re- 100 cedes.

15. A machine of the class described having, in combination, an operating member, a rotary shaft upon which said member is mounted, mechanism for causing both ends 105 of said shaft to travel in circular paths each end at any given instant having the same position and direction of movement as the other with respect to its circular path, and means whereby said mechanism may be ad- 110 justed to cause said end to have at any given instant a different position and direction of movement with respect to its path from that of the other.

16. A machine of the class described having, in combination, a shaft, an operating member mounted thereon, journal boxes in which said shaft is rotatably mounted, casings in which said boxes are slidable, eccentrics connected with said boxes, and 120 means for rotating said eccentrics, said means being constructed and arranged to permit said eccentrics to be set at various angles with respect to each other.

17. A machine of the class described having, in combination, a buffering roll, a shaft upon which said roll is mounted, journal boxes in which said shaft is rotatable, a member held from longitudinal movement with respect to said shaft, resilient means 125 130

arranged between said member and one of said boxes, a second member held similarly to the first and arranged to abut against the corresponding end of the other box, means for rotating said shaft, and means for moving one of said boxes in an orbital path.

In testimony whereof I have signed my

name to this specification in the presence of two subscribing witnesses.

WILLIAM A. BOND.
